DESIGN FOR A LAMP HEAD

Max Mache and Nathan Levinson, Chicago, Ill.

Application January 2, 1941, Serial No. 97,783

Term of patent 3½ years

To all whom it may concern:

Be it known that we, Max Mache, a national of the German Reich, and Nathan Levinson, a citizen of the United States, and residents of Chicago, in the county of Cook and State of Illinois, have invented a new, original, and ornamental Design for a Lamp Head, of which the following is a specification, reference being had to the accompanying drawing, forming a part thereof, and in which:

Fig. 1 is a side elevational view of a lamp head showing our new design;

Fig. 2 is an end elevational view of the same; and

Fig. 3 is a bottom plan view of the same as seen from below in Fig. 2.

We claim:

The ornamental design for a lamp head, as shown.

MAX MACHE.
NATHAN LEVINSON.
